UNITED STATES PATENT OFFICE.

DOLIVER M. DEAN, OF LACON, ILLINOIS.

MOLDING-MACHINE.

1,181,214.

Specification of Letters Patent.

Patented May 2, 1916.

Application filed June 9, 1911. Serial No. 632,263.

To all whom it may concern:

Be it known that I, DOLIVER M. DEAN, a citizen of the United States, residing at Lacon, in the county of Marshall and State of Illinois, have invented certain new and useful Improvements in Molding-Machines, of which the following is a specification.

This invention relates to machines for making or molding articles of plastic materials, and is especially designed for the manufacture of fence posts and similar articles from concrete or other plastic substances.

The principal object of this invention is to provide a simple and novel machine of the above character whereby fence posts may be manufactured rapidly and inexpensively without the production therein of blow holes or other defects.

A further object of this invention is to provide a machine of large capacity, that is which will turn out a number of articles in a short period of time and with a minimum expenditure of power and labor.

To the accomplishment of the foregoing and such other objects as may hereinafter appear, my invention consists in the construction and arrangement of parts herein-after particularly described and then sought to be defined by the appended claims.

An embodiment of the invention that is considered preferable is illustrated in the accompanying drawings and described in the following specification, but it is to be understood that I may vary the practical construction and details of the device within the scope of the appended claims without digressing from my inventive idea which is defined therein.

In the drawings, Figure 1 is a bottom plan view of the top mold carrying plate. Fig. 2 is a top plan view of the bottom mold carrying plate. Fig. 3 is a top plan view of the supportive frame work of the machine. Fig. 4 is a vertical section of the assembled machine taken on the plane passing through the line 4-4 of Fig. 2. Fig. 5 is a top plan view of a mold. Fig. 6 is a side elevation of a mold. Fig. 7 is a horizontal cross section of the mold taken substantially on line 7-7 of Fig. 6. Fig. 8 is a vertical cross section of the mold locking cap. Fig. 9 is a perspective view of the assembled machine, only a few of the molds and securing cups therefor being shown.

In the drawings similar characters of ref-

erence designate corresponding parts in all the figures of the drawings.

The invention provides a top and a bottom mold carrying plate which are spaced apart by tie rods and sleeves and which are provided with mold holding cups or flanges in which are held the molds. There are two series of molds running entirely around the machine which is circular in form. An automatic tamping means is provided to securely tamp or rather shake the material into a compact form. The molds are formed in two sections and hinged in a new and novel manner and are also secured between the mold carrying plates by means of a novel locking cap. The machine is driven continuously by a power connection with the lower plate.

In carrying out the invention, I provide a supporting frame or foundation A which is composed of a central plate B, having a vertically extending stud shaft C. Secured to this plate B by means of tie rods D are plates E and E' which are connected together by tie rods F. These plates E and E' are provided with yokes G in which are journaled rollers H. Formed on the end of the plate E' is the boss or projection I, in which is mounted the driving shaft J. Keyed on this shaft J is the driving pinion K.

The machine as stated hereinbefore, comprises the top and bottom mold carrying plates between which the molds are held and carried. The lower plate designated by the numeral 1 is mounted for rotation on the shaft C and is provided on its outer periphery with the gear teeth 2 which mesh with the teeth of the pinion K. On the bottom of the plate 1 are provided the inclines 3 which terminate in the abrupt vertical shoulders 4. In the drawings, four of these inclines are indicated but their number may be changed as desired. These inclines, together with the rollers H form the means whereby the material is tamped in the molds when the machine is in operation as in the rotation of the machine the inclines will run upon the rollers and thus raise the machine and when the vertical shoulders 4 are reached by the rollers the machine will drop abruptly, jogging or tamping the material in the molds compactly and thus eliminating blow holes and other defects.

The lower plate 1 is provided on its upper surface with two circular series of cups

or ring shaped flanges 5 which are preferably arranged in staggered relation as shown. The upper or top plate 6 is provided with two corresponding series of cups 5 or flanges 7 which are located on the under side thereof and are preferably somewhat smaller in diameter than the cups on the lower or bottom plate 1. The top plate 6 is further provided with openings 8 in line 10 with the cups or ring shaped flanges 7. As is evident from an inspection of the drawings, the lower plate is formed solidly and is provided with a plurality of openings, preferably four, to correspond with the flanges 10 which extend from the inner periphery of the upper mold carrying plate 6 which as shown is in the form of a circular ring. Passing through holes in these lugs 10 and also through the holes 9 in the 20 lower plate are tie rods or bolts 11 on which are placed the spacing sleeves 12 which hold the top and bottom plates the proper distance apart. The molds 13 are held in position between the top and bottom plates by 25 means of the cups or ring shaped flanges formed on the surfaces thereof. The said molds are preferably tapered, being wider at the base than at the top and are formed of two sections 14, see Fig. 7, each having 30 end portions provided with a shoulder 15 and an over-lapping projection or flap 16. These sections are provided with a hinge of peculiar construction whereby they may be opened from either side. The hinge is 35 formed in the following manner: Secured to the sides of each section are the angle iron members 17 which are positioned preferably on an incline, see Fig. 6 particularly, and provided with lugs or projections 18. 40 The angle iron members are so arranged on each section that when the two sections of the mold are placed in an assembled position the openings in the lugs 18 register. Through these openings are passed the pins 45 19. It is to be noted that these hinges are formed at both the meeting edges of both the sections and, therefore, by removal of one pin the mold may be opened at that side utilizing the other pin as the pivotal connection for the hinge. It is obvious that 50 I have provided a simple and convenient hinge construction whereby the mold may be opened from either side. Secured to the top of each mold section 55 is the pin 20 which is adapted to engage in the inclined grooves 21 which are formed in the mold locking and securing cap 22. This cap is designed to be placed upon the upper end of the mold and rotated so that 60 it is drawn down and then the mold is placed in position in the bottom cups or ring shaped flanges 5 and brought into register with the top cups or ring shaped flanges 7. The locking cap 22 is then rotated in a direction opposite to its first rotation when 65

by reason of the engagement of the pins with the inclined slots or grooves 21, it will be forced upwardly into engagement with the cups or ring shaped flanges on the under side of the top plate and thus securely 70 lock and hold the mold in position. It is obvious that by reversing this series of operations the molds may be unlocked from position and opened to allow the removal of the completed article. 75

The operation of the machine is very simple and readily understood. The plastic material is supplied from a hopper 23 or other means indicated in dotted lines in Fig. 9, the machine being driven continuously by means 80 of the driving connection shown and described. A scraping means 24 as indicated in dotted lines in Fig. 9 is provided to remove the surplus material. During the entire time that the material is being supplied to the machine the machine will be alternately lifted and dropped suddenly by means of the incline 3 and shoulders 4 engaging with the rollers H, thus tamping and jogging the material compactly in the molds, 85 eliminating any defects. This operation is continued until the molds are completely filled with thoroughly compacted material. The molds are then removed from the machine after the cap 22 is lowered by rotation 90 and are transported away to be allowed to dry and set, a plate 25 being provided in the bottom of each mold to prevent the escape of the material during the handling of the mold. New molds may be then placed in 100 position and the operation resumed.

I have shown and illustrated a device or machine wherein a large number of articles may be manufactured at once and have indicated places at which forty-two molds may 105 be placed so that forty-two posts may be manufactured at the same time. It is obvious that I may increase or decrease the number but it is to be understood that my machine is designed particularly to have a 110 large capacity and to operate up to its full capacity with minimum expenditure of power and labor. I have also provided a new and improved hinge construction whereby the molds may be opened from 115 either side, and I have also provided a new locking means whereby the molds may be secured positively and accurately in position.

The machine is composed of a very few 120 simple parts, readily assembled and taken apart and is not liable to get out of order. If it does, however, it may be readily repaired owing to the simplicity of its construction.

What I claim is:—

1. The combination with a supporting frame, of a plurality of mold carrying plates rotatably mounted thereon, a plurality of molds mounted between said plates, means 130

for reciprocating said plates and molds, and means for rotating said plates and molds.

2. The combination with a supporting frame, of a plurality of mold carrying plates 5 rotatably mounted thereon, a plurality of molds mounted between said plates, means for reciprocating said plates and molds, comprising rollers mounted on said frame and inclines on one of said plates, said rollers adapted to engage and run on said inclines, and means for rotating said plates and molds.

3. The combination with a supporting frame having a vertical stud shaft, of a plurality of mold carrying plates spaced apart 15 and secured together, one of said plates being rotatably mounted on said vertical shaft, a plurality of molds mounted between said plates, means for reciprocating said plates and molds and means for rotating said plates and molds.

4. The combination with a supporting frame, of a plurality of mold carrying plates secured together in spaced relation and rotatably mounted on said frame, a plurality 25 of molds removably mounted therebetween, means for reciprocating said plates and molds, and means for rotating said plates and molds.

5. The combination with a supporting frame, having a vertical stud shaft and also 30 a shaft supporting boss, a plurality of mold carrying plates secured in spaced relation, a plurality of molds mounted therebetween, one of said plates rotatably mounted on said 35 vertical shaft, means for reciprocating said

plates and molds, a shaft having a pinion secured thereto mounted in said boss, said pinion driving said plates.

6. The combination with a supporting frame, comprising a central plate having a vertical stud shaft and a plurality of plates disposed about said central plate, and rollers mounted on said last mentioned plates, of a plurality of mold carrying plates 40 mounted for rotation on said stud shaft, a plurality of molds mounted between said mold carrying plates, inclines having abrupt terminal shoulders formed on one of said plates, and means to rotate said plates, said 45 rollers being adapted to run on said inclines.

7. The combination with a supporting frame, said frame comprising a central frame having a vertical stud shaft and a plurality of plates disposed about said central plate, rollers mounted on said last mentioned plates, a shaft journaled in one of said last mentioned plates, a pinion secured to said last mentioned shaft, a plurality of mold carrying plates mounted for rotation 50 on said stud shaft, a plurality of molds mounted between said mold carrying plates, and inclines having abrupt terminal shoulders on one of said plates adapted to ride on 55 said rollers.

In testimony whereof I affix my signature, in presence of two witnesses.

DOLIVER M. DEAN.
